UNITED STATES PATENT OFFICE.

JOSEPH FORMAN, OF WALBROOK, MARYLAND.

SEWING-MACHINE.

1,136,001.

Specification of Letters Patent. Patented Apr. 20, 1915.

Application filed May 4, 1914. Serial No. 836,263.

To all whom it may concern:

Be it known that I, JOSEPH FORMAN, a citizen of the United States, residing at Walbrook, State of Maryland, have invented 5 certain new and useful Improvements in Sewing-Machines; and I do declare the following to be a full, clear, and exact description of the invention, such as will enable others skilled in the art to which it appertains to make and use the same.

This invention relates to improvements in sewing machines.

The object of the invention is to provide a sewing machine which employs a single 15 thread only and which is designed to form a stitch similar to ordinary hand sewing.

With this and other objects in view the invention consists of certain novel features of construction, and the combination and 20 arrangement of parts as will be hereinafter described and claimed.

In the accompanying drawings: Figure 1 represents a front elevation of this machine with the bed plate shown in section and the 25 front wall or plate of the casing removed to disclose the interior of the heads. Fig. 2 shows a longitudinal section taken substantially on the line 2—2 of Fig. 1. Fig. 3 is an enlarged detail vertical section through 30 one of the needle bars and the needle releasing member and guide arranged adjacent thereto with the needle in lowered position. Fig. 4 is a similar view with the needle in elevated position. Fig. 5 is a 35 transverse vertical section taken on the line 5—5 of Fig. 4: Fig. 6 is a similar view taken on the line 6—6 of Fig. 4. Fig. 7 is a transverse section taken on the line 7—7 of Fig. 4. Fig. 8 is a horizontal section taken on the 40 line 8—8 of Fig. 2 looking downward. Fig. 9 is a similar view showing the thread drawing attachment in operative position. Fig. 45 10 is a transverse section taken on the line 10—10 of Fig. 9. Fig. 11 is a similar view taken on the line 11—11 of Fig. 8. Figs. 12, 13, 14, 15 and 16 show diagrammatic views illustrating the various positions of the needle bars during one cycle of the operation of the machine whereby two stitches are 50 formed one on the lower face of the work and one on the upper face.

In the embodiment illustrated duplicate needle operating mechanism is shown arranged above and below the bed plate or 55 work table 1, the construction of which is exactly alike each comprising a hollow

L-shaped bracket 2 having a head 3 cast upon one end of the horizontal arm 2' thereof and a main shaft 4 mounted in suitable bearings within said horizontal arm 2', a 60 bevel gear 5 being fixed to said main shaft preferably near its rear end. A band or driving wheel 6 is secured to the rear end of the upper main shaft 4 which projects through one end of the arm 2' and whereby 65 motion is imparted to said upper main shaft 4 from any suitable source (not shown).

A vertical bar or rod 7 is rotatably mounted in suitable bearings in the hollow communicating upright arms of the brackets 2 70 and is provided with bevel gears 8 positioned to mesh with the bevel gears 5 on the rear ends of the upper and lower main shafts 4 whereby motion is transmitted from the upper main shaft to the lower main 75 shaft as is clearly shown in Fig. 2.

Mounted on the front ends of these main shafts 4 within the heads 3 are large bevel gears 9 which mesh with similar smaller gears 10 mounted in suitable vertically disposed bearings 11 in the heads 3 which are here shown formed in castings secured to said heads and which castings are also provided with horizontally disposed bearings 12 in which are revolvably mounted smaller 85 bevel gears 13 which mesh with the gears 10 for a purpose to be described. These gears 9, 10 and 13 have the teeth thereof so proportioned that one revolution of the large gears 9 produces two complete revolutions 90 of the small gears 13 for the purpose hereinafter to be described.

The large gears 9 have several teeth omitted as shown at 14 forming dwells or gaps for arresting the movement of the needle 95 bars controlled thereby as will be hereinafter described.

Mounted to slide vertically in said heads 3 are needle bars 15 which are adapted to move toward and away from each other at 100 predetermined intervals for advancing and retracting a double pointed needle 16 carried by one of said bars which are adapted to alternately receive and hold the needle for passing it back and forth through the 105 needle opening in the work table and through the work disposed thereon in a manner to be described.

An eccentrically disposed stud 17 extends laterally from the outer face of each gear 13 110 and has pivotally connected therewith one end of a pitman 18 the other end of which is

pivotedly connected with a casting 19 fixed on the needle bar 15 and by means of which the needle bar is actuated through its main shaft from the driving wheel 6. The upper 5 and lower needle bars which move toward and away from each other are each provided at its needle engaging end with a needle socket 20 one side wall of which is formed by a laterally movable clamping jaw 21 pivotally mounted at its inner end at the inner end of the socket and which is yieldably held in operative position by a spring 10 pressed yoke 22. This yoke 22 as shown comprises two laterally spaced U-shaped members 23 and 24 the free ends of the legs 15 of which are connected together and to each other by an apertured cross bar 25. The cross bars of the members 23 and 24 encircle the gripping jaw 21 and a headed stud or 20 screw 26 passes through the aperture in the cross bar 25 which connects said members 23 and 24 and is engaged with the needle bar at a point diametrically opposite the jaw 21.

A comparatively strong coiled spring 27 25 encircles this stud 26 between the inner face of the cross bar 25 and the needle bar with which it is connected and exerts its tension to force said yoke in a direction opposite to the opening direction of the jaw 21 and thereby firmly but yieldably holds said jaw closed to reliably clamp one end of the needle 16.

A needle releasing member 28 is mounted in the path of the yoke 24 and is here shown 30 in the form of a substantially L-shaped plate having a slot 29 extending longitudinally throughout both arms thereof and which is adapted to form guides for the head of the stud 26 which passes through said slot. The 35 long arm of this member 28 is provided near its junction with the short arm with a laterally extending projection 30 which is positioned in the path of the cross bar 25 of the yoke 22 so that when the needle bar 40 reaches a predetermined point this projection comes in contact with the cross bar 25 of the yoke and forces it inward against the tension of the spring 27 thereby moving the cross bars of the members 23 and 24 out of 45 engagement with the clamping jaw 21 thereby releasing the needle from said clamping jaw and permitting it to be drawn out of the socket 20 in a manner and for a purpose to be described. This releasing action of the 50 jaws 21 takes place when the needle bars which carry them reaches the extreme limit of their stroke in one direction, that is at the end of their stroke which approaches the work table. In Fig. 3 the releasing device 55 is shown in the act of releasing the needle from the upper needle bar and Figs. 4 5 and 6 show it in clamped operative position and with the needle in raised position ready for its down stroke.

60 The gap 14 formed by the omission of the

teeth from the gear wheel 9 is so disposed as to arrest the movement of the needle bar with which it is connected at predetermined intervals.

A thread drawing or tightening attachment 65 is here shown comprising two mutilated intermeshing gears 31 and 32, one of which is fixed to the vertical shaft 7 in a plane above the plane of the upper face of the table 1 and parallel therewith. The other gear 32 is fixed on a stud shaft 33 revolubly mounted in vertically spaced bearings in the form of apertured lugs 34 and 35 extending laterally from the outer face of the upright arm of the upper bracket 2. 70 The gear 32 extends through an opening in said bracket arm as shown in Figs. 8, 9 and 11 and is provided with an angular arm 36 the free end of which has a resilient wire rod 37 mounted therein. This rod 37 has a 75 laterally extending finger 38 at its free end for preventing the thread loop shown at 40 from slipping off said end. A coiled spring 39 is connected at one end with the arm 36 of the attachment and at its other end to a 80 stud suitably positioned on the bed plate to adapt said spring to exert its tension for returning the rod 37 to normal position after it has been actuated by the engagement of the gears 31 and 32 on the rotation of 85 shaft 7.

The needle operating mechanism being shown in duplicate and both driven by a single band wheel 6 motion being imparted direct therefrom to the upper main shaft 4 100 and to the lower main shaft through the vertical shaft 7 and the bevel gears thereon meshing with bevel gears on said main shafts, one of said shafts is rotated in one direction and the other in the opposite direction as shown by the arrows in Figs. 12 105 to 16.

In the use of this machine when the parts are in the position shown in Figs. 3 and 12 with the needle 16 in the position which it 110 assumes when being transferred from the upper to the lower needle bar and with the opposed points of said needle in the sockets of both needle bars and the yoke engaging projections engaging said yokes and forcing 115 them against the tension of springs 27 to open the needle clamps 21, the gap or dwell 14 in the upper large gear wheel 9 is in engagement with the smaller gear 10 whereby 120 said gear 10, the gear 13 and upper needle bar controlled thereby stand still a sufficient time to permit the needle 16 to be released and withdrawn from its socket 20 and transferred to the socket 20 of the lower mechanism. The length of time the needle bar 125 stands still is controlled by the number of teeth omitted to form the dwell 14. Thus it will be seen that when the dwell 14 of the upper gear 9 is ready for engagement with gear 10 the dwell 14 in the lower gear 9 is 130

5 diametrically opposite its coöperating gear 10 (see Fig. 12) and both needle bars 15 are at the extreme limit of their inward stroke with the yokes 22 thereof opposite the projections 30 on the needle releasing members whereby both latches or jaws 21 are opened. The continued operation of the driving wheel 6 sufficient to cause the large gears 9 to make a quarter revolution will advance 10 the work (by means not shown) and permit the needle 16 to be grasped and locked in the socket of the lower needle bar and the parts to assume the position shown in Fig. 13 with the yokes moved out of engagement with the 15 projections. This movement draws the needle downward through the opening O in table 1 and through the work disposed thereon. Another quarter turn of large gears 9 advances the work on the table and passes 20 needle 16 up through table 1 and work thereon into the position shown in Fig. 14 thereby forming the stitch S of Fig. 10. The dwell 14 of the upper gear 9 is then diametrically opposite its coöperating gear 10 and 25 the dwell 14 in the lower gear 9 is engaged with its gear 10 thereby causing its needle bar to stand still long enough for the needle 16 to be withdrawn from the socket of the lower needle bar and be raised and clamped 30 in the socket of the upper needle bar.

Another quarter turn of gears 9 advances the work and positions the parts as shown in Fig. 15 with the needle 16 ready to descend to form the stitch s of Fig. 10. Another quarter turn of gears 9 causes said needle to descend as shown in Fig. 16 whereby the parts are again in the position shown in Fig. 14, the large gears having made one revolution and the small gears 13, which actuate 40 the needle bars, two revolutions.

During the stitch forming operation above described the thread T which is threaded through the eye 16' of the needle 16 forms loop 40 when the large gears have made 45 three quarters of a revolution and the teeth of gears 31 and 32 are thereby brought into mesh causing the arm 37 which lies in the path of said loop to make an outward sweep as shown in Fig. 9 and thereby draw the 50 thread to tighten it sufficiently to form the stitches S and s. After this arm has been so actuated the further turning of shaft 7 releases said arm and the spring 39 returns it to normal position as shown in Fig. 8.

55 In the use of this machine when the parts are in the position shown in Figs. 3 and 12 with the needle 16 in the position which it assumes when being transferred from the upper to the lower needle bar and with the 60 opposed points of said needle in the sockets of both needle bars and the yoke engaging projections engaging said yokes and forcing them against the tension of springs 27 to open the needle clamps 21, the gap or dwell 65 14 in the upper large gear wheel 9 is ready

for engagement with the smaller gear 10 which occurs on the further turning of the gears 9 whereby said gear 10, the gear 13 and upper needle bar controlled thereby stand still a sufficient time to permit the 70 needle 16 to be released and withdrawn from its socket 20 and transferred to the socket 20 of the lower mechanism. The length of time the needle bar stands still is controlled by the number of teeth omitted to form the 75 dwell 14. Thus it will be seen that when the dwell 14 of the upper gear 9 is in engagement with gear 10 the dwell 14 in the lower gear 9 is diametrically opposite its coöperating gear 10 (see Fig. 12) and both needle 80 bars 15 are at the extreme limit of their inward stroke with the yokes 22 thereof opposite the projections 30 on the needle releasing members whereby both latches or jaws 21 are opened. The continued operation 85 of the driving wheel 7 sufficient to cause the large gears 9 to make a quarter revolution will advance the work (by means not shown) and permit the needle 16 to be grasped and locked in the socket of the 90 lower needle bar and the parts to assume the position shown in Fig. 13 with the yokes moved out of engagement with the projections. This movement draws the needle 95 downward through the opening O in table 1 and through the work disposed thereon. Another quarter turn of large gears 9 advances the work on the table and passes needle 16 up through table 1 and work thereon into the position shown in 100 Fig. 14 thereby forming the stitch S of Fig. 10. The dwell 14 of the upper gear 9 is then diametrically opposite its coöperating gear 10 and the dwell 14 in the lower gear 9 is ready for engagement with its gear 10 105 which causes its needle bar to stand still long enough for the needle 16 to be withdrawn from the socket of the lower needle bar and be raised and clamped in the socket of the upper needle bar. Another quarter 110 turn of gears 9 advances the work and positions the parts as shown in Fig. 15 with the needle 16 ready to descend to form the stitch s of Fig. 10. Another quarter turn of gears 9 causes said needle to descend as 115 shown in Fig. 6 whereby the parts are again in the position shown in Fig. 14, the large gears having made one revolution and the small gears 13, which actuate the needle bars, two revolutions.

120 During the stitch forming operation above described the thread T which is threaded through the eye 16' of the needle 16 forms loops 40 when the large gears have made three quarters of a revolution and the teeth of gears 31 and 32 are thereby brought into mesh causing the arm 37 which lies in the path of said loop to make an outward sweep as shown in Fig. 9 and thereby draw the thread to tighten it sufficiently to form 130

the stitches S and s. After this arm has been so actuated the further turning of shaft 7 releases said arm and the spring 39 returns it to normal position as shown in Fig. 8.

I claim as my invention:

1. In a sewing machine the combination of two alined needle bars having needle receiving sockets and between which bars the material is fed, a double pointed needle adapted to be carried alternately in said sockets, a laterally movable needle clamping jaw carried by each bar, a spring pressed yoke encircling said jaw, and means arranged in the path of said yoke for engaging it at predetermined intervals to release the needle.
2. In a sewing machine, the combination of two alined needle bars having needle receiving sockets and between which bars the material is fed, a double pointed needle adapted to be carried alternately in said sockets, a laterally movable needle clamping jaw carried by each bar, a spring pressed yoke encircling said bar and jaw, a stud extending laterally from said bar at a point opposite said clamping jaw, a spring on said stud between said bar and said yoke for yieldably holding said jaw in closed

position, and means in the path of said yoke 30 for releasing said jaw.

3. In a sewing machine, the combination of two alined needle bars having needle receiving sockets and between which bars the material is fed, a double pointed needle 35 adapted to be carried alternately in said sockets, a laterally movable needle clamping jaw carried by each bar, a spring pressed yoke encircling said bar and jaw, a stud extending laterally from said bar 40 at a point opposite said clamping jaw, a spring on said stud between said bar and said yoke for yieldably holding said jaw in closed position, a slotted member arranged with the head of said stud extending 45 through the slot in said member and said member having a laterally extending projection arranged in the path of said yoke to release said jaw at predetermined intervals.

In testimony whereof I have hereunto set my hand in presence of two subscribing witnesses.

JOSEPH FORMAN.
